SHEDDING MECHANISM FOR CIRCULAR LOOMS

Joanny Jabouley and Robert Yeadon, Spondon, near Derby, England, assignors to Celanese Corporation of America, a corporation of Delaware

Application August 3, 1935, Serial No. 34,575
In Great Britain August 22, 1934

7 Claims. (Cl. 139—13)

This invention relates to shedding mechanism for the weaving of selvedges in circular looms.

Although one of the advantages of a circular loom is that it enables the weaving of a piece of fabric of a width equal to the weaving periphery of the loom to be woven by continuous motion, such fabric usually has to be split lengthwise either into a single piece or into a plurality of pieces, depending upon the periphery of the loom and the use to which the fabric is to be put. Since the weft is carried continuously round the tubular fabric in one direction, the loom does not weave a selvedge as in the case of an ordinary loom in which the weft is picked 10 from side to side of the fabric in opposite directions. Therefore when the tubular fabric is split there is the danger of the edges of the fabric unravelling.

The present invention has for its object to provide means whereby unravelling can be avoided when the fabric is split, the means according to the invention being adapted for use in a loom in which shedding is effected by means of shedding wheels or like pressing means disposed near the front of each shuttle and alternately at opposite sides of the warp sheet, the wheels or the like working in conjunction with a reed on which some of the threads are free to move between the reed dents while others are restrained by passing through holes in the dents. The shedding wheels or the like operate to press the warps which are free to move first to one side of one shuttle and then to the other side of the succeeding shuttle, in each case forming a shed into which the shuttle can enter and further separate the warps. The invention provides a device which, in conjunction with such shedding mechanism, produces a crossing of pairs of warp threads in the part of the fabric that will 30 form the selvedges.

The device according to the invention comprises a reed or comb conveniently mounted in the same structure with the perforated reed dents of the shedding mechanism, the dents of the comb 45 terminating in eyes in the same circumferential line as the eyes of the main reed dents. Adjacent the comb having the eyed dents is arranged another reed or comb capable of a slight movement in a circumferential direction.

In advance of alternate shedding wheels or like shedding elements (hereafter referred to solely as "shedding wheels") on one side of the warp circle, a cam or other device is mounted to come into engagement with the movable reed 50 or comb so as to move the reed or comb by ap-

proximately the space between a pair of dents. An opposite circumferential movement of the reed or comb occurs when the cam or other device is passed, so that at each shedding wheel of the one series a movement in one direction or 5 the other takes place in the threads controlled by the reed or comb.

Some of the warp threads are threaded through the eyes of the one comb of the device while the remainder are not so threaded. These remaining threads are carried by the movement of the other reed or comb to one side of the eyed dents, so that upon engagement of the warp threads by the one series of shedding wheels the non-threaded warp threads are crossed over the 15 threaded warp threads to form a shed.

After passage of the shuttle through the shed, the threads are shedded by a wheel of the other series for the passage of the next shuttle. The movable reed or comb is then returned by approximately the space between a pair of dents to its original position, so bringing the movable warp threads to the other side of the threads entered in the eyes of the comb. The succeeding shedding wheel then deflects the movable 20 warp threads to form another shed, after which shedding is effected by the next wheel of the second series, and so on.

The wheels of the second series operate to shed all the threads normally, only the wheels 30 of the first series producing crossed sheds. The result is that at every other pick corresponding to the operation of the first series of wheels the threads in the eyed comb are crossed over the adjacent movable threads to give a doup effect. 35 This doup effect may extend over, say, 12-24 warp threads, so that if the woven fabric is split along the centre of the doup some 6-12 warp threads at each side of the split are twisted with each other at every fourth pick and serve to grip a 40 substantial length of the severed weft threads. Any tendency of the warps to unravel is thus reduced when the fabric is split within the doup portion.

One form of apparatus according to the invention will now be described in greater detail with reference to the accompanying drawing in which Figure 1 is a diagrammatic part cross-sectional elevation of part of a circular loom employing rotating shuttles; Figure 2 is a diagrammatic plan view of part of the circular loom shown in Figure 1; Figure 3 is a part cross-sectional elevation of a detail of Figure 1, on larger scale, taken along 3—3 to Figure 4; Figures 4 to 7 are diagrammatic plan views indicating the mode 45 50 55 of operation of the shedding mechanism.

of operation of the mechanism shown in Figures 1 and 3; while Figure 8 is a diagrammatic representation of fabric woven according to the invention.

5 Referring to Figure 1, warp threads 6 unwinding from beams or like supply packages (not shown) are spaced evenly round the top of the loom by a circular comb 7 and proceed downwardly in cylindrical arrangement to the fabric 8, along the fell 9 of which weft is laid by a number of rotating shuttles (three, 10, 11, 12 shown in Figure 2). The fabric 8 is supported below the fell 9 by the edge of a ring 14 outstanding from the central shaft 15 of the loom.

15 Each shuttle is propelled round the loom by vane wheels 16 secured to a driving shaft 17, the driving shaft being driven in turn from a radially disposed spindle 18 supported by a rotatable ring 19, which is driven round the loom 20 at the rate at which it is desired to propel the shuttles by an electric motor 20. The drive from the electric motor 20 to the rotatable ring 19 is transmitted by belt gearing 21 and vertical shaft 22. For further details as to the operation of 25 the vane wheels and associated mechanism, reference may be made to U. S. application S. No. 315,599 filed July 16, 1935.

The warp threads 6 are shedded progressively round the loom to receive the shuttles 10—12 . . . 30 by shedding wheels 23, 24 which co-operate with a circular reed-like member 25 of the type described in U. S. Patent No. 2,008,913, supported by a spider 26 outstanding from the central shaft 15 of the loom.

35 U. S. Patent No. 2,008,913 describes in detail the shedding operation effected by the shedding wheels 23, 24 and the member 25, and the following description will therefore give merely a brief outline of the salient features of the shedding 40 operation.

The circular reed-like member 25 comprises a series of closely spaced dents 27 each of which is formed with an eye 28 at a point midway along its length and coinciding with the normal unshedded line 29 of the warp threads (see Figure 45 3). Alternate warp threads are threaded through the eyes 28 of the dents 27, and thus are fixed with respect to lateral movement, while the remaining threads are passed between adjacent dents and 50 are free to move radially along the spaces between the dents.

The shedding wheels 23 are carried round the loom inside the warp circle by a rotatable spider 30 which is driven round the central shaft 15 at the rate of rotation of the shuttles while the shedding wheels 24 are carried round the loom outside 55 the warp circle by standards 31 supported by the rotatable ring 19.

One inner shedding wheel 23 is mounted in association with each alternate shuttle, while one outer shedding wheel 24 is mounted in association with each remaining shuttle, the disposition of each shedding wheel being such that its periphery projects beyond the normal line 29 of the warp threads 6 with the result that all the warp threads are pushed radially towards and away from the loom axis, respectively, at alternate 65 shuttles.

Since, however, alternate threads are fixed in the normal line 29 with respect to lateral movement, the free threads only move radially on being pressed with the result that the warp threads are shedded at each shuttle (see Figure 3). The shedding is indicated diagrammatically in Figure 2. The noses of the shuttles enter the sheds

thus formed in advance thereof, and the shuttle bodies push the divided threads sideways to form a shed of the requisite width, as indicated clearly in Figure 3.

In order to form a doup selvedge to enable 5 the tubular fabric 8 to be cut without fraying of the cut edges, a set of six adjacent dents 27 are removed from the member 25 to form a gap. Over the gap thus formed six short dents 33 are fixed so as to form an open-ended comb, the dents 10 33 lying in the same radial planes as the removed dents. The outermost ends of the dents 33 are formed with eyes 34 through which are passed alternate warp threads A from the twelve threads passing through the gap. The length 15 of the dents 33 is such that the warp threads A are held in the normal line 29, as shown in Figures 3 to 7.

Pivoted on the member 25 is a closed-ended comb 36, comprising seven dents 37 fixed into 20 cross members 38, 39, the comb extending over the six dents and being pulled in a clockwise direction against a stop 40 by a tension spring 41. The remaining six warp threads B are passed 25 between the dents 37 of the comb 36, as shown in Figures 3 to 7, and are free to move radially along the length of the dents 37.

To commence the selvedge-forming operation, a raised cam 42 formed on the periphery of the spider 30 in the vicinity of the shuttle 10 is carried by the rotation of the spider against a bowl 43 rotatably mounted on an extension of the cross member 39, and swings the comb 36 in an anti-clockwise direction so that each of the warp threads B is directed to the left-hand side of a 35 40 dent 33.

The outer shedding wheel 24, in association with the shuttle 10, now pushes all the warp threads inwardly along the comb 37 thus forming a shed for the reception of the shuttle 10, as 40 shown in Figures 3 and 4.

On passage of the shuttle 10 and consequent laying of weft thereby between the divided threads A and B the bowl 43 reaches the end of the cam 42 and is swung in a clockwise direction under the influence of the tension spring 41. Just as the comb 36 commences this clockwise movement, however, the inner shedding wheel 23 in association with the next shuttle 11 engages the threads B and pushes them outwardly again along the dents 37 to a point beyond the ends of the dents 33, as shown in Figure 5, thus forming a reversed shed for the reception of the next shuttle 11.

On passage of the shuttle 11, the comb 36 is allowed to swing against the stop 40 and thus reaches a position in which the threads B can be directed to the right-hand side of the dents 33 across the fixed threads A. The outer shedding wheel in association with the succeeding shuttle 60 12 now engages the threads and pushes them inwardly along the right-hand sides of the dents 33 thus forming a shed for the reception of the shuttle 12.

On passage of the shuttle 12, a further raised cam 45, formed on the spider 30 commences to push the comb 36 in a clockwise direction in readiness for redirection of the threads B to the left-hand side of the dents 33. As the cam 45 moves the comb, the inner shedding wheel 23 in association with the next shuttle 13 engages the threads and pushes the threads B outwardly again to a point beyond the ends of the dents 33, 70 thus forming a shed for the reception of the shuttle 13.

At the next shuttle the threads B are pushed inwardly again along the left-hand sides of the dents 33 (as shown in Figure 4), and the above described operations are repeated.

5 It will be understood that the free warp threads B are caused to lie first to one side and then to the other of the fixed threads A, a pick of weft being laid between the two sets of threads after every shedding movement. The effect thus obtained is shown clearly in Figure 8, the interlocking of the threads preventing the edges of the fabric unravelling on being cut through the selvedge. The cutting of the fabric may conveniently be effected along the line C—C thus providing selvedges of equal width at the two edges of the cut fabric.

10 While the above description has been directed to forming a doup selvedge at one point only of the periphery of the loom, it is to be understood that such selvedge can be formed at any desired intervals round the loom. Thus if the tubular fabric woven in the circular loom is to be cut lengthwise to form a single sheet, one selvedge of the type described is sufficient. If, 15 on the other hand, two separate fabrics are desired, two selvedges will be formed, and so on.

20 If desired the doup mechanism according to the invention can be incorporated in a circular loom for the purpose of producing stripe patterns in the fabric, the stripes being of any desired width. By substituting for the dents 27 short dents 33, and fitting combs 36 completely round the loom periphery the whole of the fabric produced by the loom can be woven on the 25 doup principle.

25 It is to be understood that while the apparatus according to the invention has been described in connection with a circular loom employing rotating shuttles, similar mechanism could be employed in a circular loom in which the shuttles are held stationary while the warp threads rotate about the loom axis.

30 The warp threads in the selvedge formed according to the invention may be the same as the threads in the remainder of the fabric, or special selvedge threads may be introduced into the warp at this point, for example for the purpose of strengthening the edges of the fabric or for the 35 purpose of enabling the fabric to be identified.

35 The invention has, for simplicity, been described in connection with the crossing-over of alternate warp threads to form the doup selvedge according to the invention. It will be understood, however, that a single thread could be 40 crossed with two or more other threads, or two or more threads could be crossed with one or more threads in any desired order.

45 What we claim and desire to secure by Letters Patent is:—

50 1. In a circular loom having a warp-shedding reed of the type described, a comb disposed in a gap in the reed and having a series of eyed dents for holding a set of spaced warp threads at a fixed radial distance from the loom axis, a 55 further member disposed in the vicinity of the comb and comprising a series of longer dents for guiding a further set of spaced warp threads radially with respect to the loom axis, shedding means disposed alternately at opposite sides of the warp sheet and adapted to move said further set of threads radially inwardly and outwardly past the fixed set of threads to form successive sheds on the inside and outside of said 60 fixed threads after the laying of a pick of weft in a shed, and means for effecting relative circumferential motion between the further member and the comb after the laying of 65

70 cumferential motion between the further member and the comb after the laying of a pick of weft in each of the sheds formed to the outside of the fixed threads so as to pass each thread of the further set circumferentially across a corresponding thread of the fixed set before the formation of the next shed. 75

2. In a circular loom having a warp-shedding reed of the type described, a comb disposed in a gap in the reed and having a series of eyed dents for holding a set of spaced warp threads at a fixed radial distance from the loom axis, a further member comprising a series of longer dents and pivoted on the reed above the comb, 10 said pivoted member being adapted to guide a further set of spaced warp threads radially with respect to the loom axis, shedding means disposed alternately at opposite sides of the warp sheet and adapted to move said further set of threads radially inwardly and outwardly past the 15 fixed set of threads to form successive sheds on the inside and outside of said fixed threads after the laying of a pick of weft in a shed, and means for moving said pivoted member about its pivot after the laying of a pick of weft in each of the 20 sheds formed to the outside of the fixed threads so as to pass each thread of the further set circumferentially across a corresponding thread of the fixed set before the formation of the next 25 shed. 30

3. In a circular loom having a warp-shedding reed of the type described, a comb disposed in a gap in the reed and having a series of eyed dents for holding a set of spaced warp threads at a fixed radial distance from the loom axis, a further member comprising a series of longer dents and pivoted on the reed above the comb, 35 said pivoted member being adapted to guide a further set of spaced warp threads radially with respect to the loom axis, a cam follower mounted on said pivoted member, shedding means disposed alternately at opposite sides of the warp sheet and adapted to move said further set of threads radially inwardly and outwardly past the 40 fixed set of threads to form successive sheds on the inside and outside of said fixed threads after the laying of a pick of weft in a shed, and a cam adapted to engage the follower so as to move said pivoted member about its pivot after the laying of a pick of weft in each of the sheds 45 formed to the outside of the fixed threads so as to pass each thread of the further set circumferentially across a corresponding thread of the fixed set before the formation of the next 50 shed. 55

4. In a circular loom having a warp-shedding reed of the type described, a comb disposed in a gap in the reed and having a series of eyed dents for holding a set of spaced warp threads at a fixed radial distance from the loom axis, a further member disposed in the vicinity of the comb and comprising a series of longer dents for guiding a further set of spaced warp threads radially with respect to the loom axis, shedding wheels disposed alternately at opposite sides of the warp sheet, means for effecting relative circular motion with respect to the loom axis between the shedding wheels and the warp threads so as to move said further set of threads radially inwardly and outwardly past the fixed set of threads 60 to form successive sheds on the inside and outside of said fixed threads after the laying of a pick of weft in a shed, and means for effecting relative circumferential motion between the further member and the comb after the laying of 65

- a pick of weft in each of the sheds formed to the outside of the fixed threads so as to pass each thread of the further set circumferentially across a corresponding thread of the fixed set before the formation of the next shed.
5. In a circular loom having a warp-shedding reed of the type described, a comb disposed in a gap in the reed and having a series of eyed dents for holding a set of spaced warp threads 10 at a fixed radial distance from the loom axis, a further member disposed in the vicinity of the comb and comprising a series of longer dents for guiding a further set of spaced warp threads radially with respect to the loom axis, a ring, 15 means on said ring for positioning shuttles between the warp threads, means for imparting relative circular motion with respect to the loom axis between the ring and the warp threads, shedding wheels in association with said ring and disposed alternately at opposite sides of the warp sheet, said shedding wheels being adapted to 20 push the further set of threads radially inwardly and outwardly past the fixed set of threads to form successive sheds on the inside and outside 25 of said fixed threads after the laying of a pick of weft in a shed, and a cam in driving connection with said ring and adapted to effect relative circumferential motion between the further member and the comb after the laying of a pick 30 of weft in each of the sheds formed to the outside of the fixed threads so as to pass each thread of the further set circumferentially across a corresponding thread of the fixed set before the formation of the next shed.
35. 6. In a circular loom having a warp-shedding reed of the type described, a comb disposed in a gap in the reed and having a series of eyed dents for holding a set of spaced warp threads at a fixed radial distance from the loom axis, a further member comprising a series of longer dents and pivoted on the reed above the comb, said pivoted member being adapted to guide a further set of spaced warp threads radially with 40 respect to the loom axis, a cam follower mounted 45 on said pivoted member, a ring, means on said ring for positioning shuttles between the warp threads, means for driving said ring around the loom, a set of shedding wheels in association with the ring and disposed at one side of the warp sheet, a further set of shedding wheels cooperating 50 with said first-mentioned set and disposed at the other side of the warp sheet, said shedding wheels being adapted to push in turn the fur-

ther set of threads radially inwardly and outwardly past the fixed set of threads to form successive sheds on the inside and outside of said fixed threads after the laying of a pick of weft in a shed, and a cam in association with 5 said shedding wheels and adapted to engage the follower on the pivoted member to move said member about its pivot after the laying of a pick of weft in each of the sheds formed to the outside of the fixed threads so as to pass each 10 thread of the further set circumferentially across a corresponding thread of the fixed set before the formation of the next shed.

7. In a circular loom having a warp-shedding reed of the type described, a comb disposed in a 15 gap in the reed and having a series of eyed dents for holding a set of spaced warp threads at a fixed radial distance from the loom axis, a further member comprising a series of longer dents and pivoted on the reed above the comb, said 20 pivoted member being adapted to guide a further set of spaced warp threads radially with respect to the loom axis, a cam follower mounted on said pivoted member, a ring, means on said ring for positioning shuttles between the warp 25 threads, means for driving said ring around the loom, a set of shedding wheels in association with the ring and disposed at one side of the warp sheet, a freely rotatable ring mounted at the other side of the warp sheet, a further set 30 of shedding wheels mounted on said freely rotatable ring and cooperating with said first-mentioned set, said shedding wheels being adapted to push in turn the further set of threads radially inwardly and outwardly past the fixed 35 set of threads to form successive sheds on the inside and outside of said fixed threads after the laying of a pick of weft in a shed, a freely rotatable driving wheel on said freely rotatable ring, said wheel being engaged by a shedding 40 wheel at the other side of the warp sheet to effect rotation by the freely rotatable ring, and a cam on said freely rotatable ring and adapted to engage the follower on the pivoted member to move said member about its pivot after the laying 45 of a pick of weft in each of the sheds formed to the outside of the fixed threads so as to pass each thread of the further set circumferentially across a corresponding thread of the fixed set before the formation of the next shed. 50
